TERMINAL BLOCK AND SAFETY LIGHT FOR
ELECTRIC SURFACE COOKING UNITS

Arthur H. Kitson, Grosse Pointe, Mich.

Application April 20, 1946, Serial No. 663,693

7 Claims. (Cl. 177—311)

1

This invention relates to a terminal block and safety light for an electric surface cooking unit and has particular reference to a terminal block for a unit of this kind wherein provisions are made for a safety light for the unit which is constructed and arranged so that the light is on at all times whenever the unit or any part thereof is energized.

A great many accidents occur in connection with the use of embedded element type of electric surface cooking units due to the fact that these units do not glow when they are on low heat. While many suggestions have heretofore been made to overcome this difficulty, none of such suggestions has proved satisfactory. The present invention contemplates a terminal block and safety light unit in which the light is arranged to throw a beam of light through the openings in the surface cooking unit whenever any part of the circuit thereof is energized, thus providing a fool-proof and inexpensive arrangement.

Principal objects of the invention, therefore, are to provide:

A terminal block and safety light unit for an electric surface cooking element;

A safety light unit for an electric surface cooking unit which is constructed and arranged so that whenever any part of the cooking unit is energized, a beam of light will be visible through the openings therein;

An electric surface cooking unit having a terminal block and safety light unit associated therewith in which the terminal block provides a mounting for the safety light and in which the light is shielded from the heat of the cooking elements; and

A safety light for an electric surface cooking unit which is simple in construction, efficient in operation and inexpensive to manufacture and assemble.

Other and further objects of the invention will be apparent from the following description and claims and will be understood by reference to the accompanying drawings, of which there are two sheets, which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

In the drawings

2

Fig. 1 is a side elevational view of a device embodying the invention;

Fig. 2 is a plan view thereof;

Fig. 3 is a view taken generally along the line 3—3 of Fig. 2, but with certain parts shown in elevation;

Fig. 4 is a fragmentary bottom plan view of the terminal block and light unit with the reflector shield omitted;

10 Fig. 5 is a sectional view taken along the line 5—5 of Fig. 2;

Fig. 6 is a side elevational view of a terminal block embodying a modified form of the invention;

15 Fig. 7 is a sectional view taken along the line 7—7 of Fig. 6; and

Fig. 8 is a circuit diagram illustrating a wiring arrangement for the heating element and the light that might be employed where the heating element comprises a single resistance element.

An electric surface cooking unit embodying the invention comprises a plurality of embedded element type of electric resistance heaters arranged in the form of spaced rings 10 and 12 and supported upon a frame 14 which in turn is connected with a supporting ring 16 which seats upon the ledge around an opening in the top surface of a cooking range. Annular spaces 18, 20 and 22 are formed by the rings 10, 12 and 16 and the button 24 which partially fills the opening in the center ring 10.

Conductors 26, 28 and 30 at one end thereof are electrically connected to the resistance elements encased in the rings 10 and 12 and at their other ends are connected to a terminal block 32 which is provided with a plurality of holes as shown in Fig. 1, whereby the current conductors in the range may be electrically connected to the ends of the conductors 26, 28 and 30 on the terminal block 32. Screws 34 are associated with the terminal block ends of the conductors, whereby the conductors in the range may be fastened to the ends of the conductors in the terminal block 32. The terminal block 32 is made of an electrically non-conducting material, such as porcelain. It is moulded to form a recess 36 and an electric socket 38, the socket 38 being disposed so that the bulb 40 mounted therein may be positioned in the recess 36. The screw thread portion of the socket 38 defined by a metal sleeve is connected by a conductor 42 to the conductor 28.

The head of a bolt 44 arranged in the bottom of the socket 38 forms the other terminal for the light bulb 40. A conductor 46 connected to an external portion of the bolt 44 is adapted to be connected to the safety light terminal on the usual switch which controls the flow of electric current to the unit. The safety light switch terminal (not shown) is constructed and arranged so that the circuit through the light 40 will be

closed whenever any part of the circuit through the heating elements of the rings 10 and 12 are closed.

A reflector shield 50 is detachably secured to the underside of the frame 14 and in spaced relation therewith by means of a wing nut 52 fastened on a bolt 54 which in turn may be carried by the button 24. The reflector shield 50 is constructed to form a trough or channel 60 for conducting and directing light rays from the light 40 to the openings 20 and 22. For this purpose, the shield 50 which may be formed of sheet metal is suitably formed to provide the channel 60 and the ends of the channel are formed so as to fit around the terminal block 32 as shown in Fig. 3 which shows the terminal block in section and the shield 50 in elevation, except for a cut away portion in the center thereof. That is, the outer end of the trough 60 communicates and is in line with the recess 36 and the terminal block so that the light emitted by the bulb 40 will be confined by the side walls of the trough 60 and directed toward the openings 20 and 22 in the surface unit.

In the modification illustrated in Figs. 6 and 7, the terminal block 132 is much like that illustrated in the embodiment just described, except that the back and bottom wall of the recess 136 in which the light 40 is arranged are formed by a metallic reflector 138 which is secured by screws 140 to the terminal block. Integral portions of the terminal block form the side walls of the recess 136 and a receptacle for the light 40. This terminal block and light is adapted to be employed in the same kind of an arrangement as illustrated in Figs. 1 to 3, except that the trough or channel for directing the light rays from the light 40 through the openings adjacent the rings 10 and 12 would be formed slightly differently than shown in Fig. 3 so as to fit the form of construction as illustrated in Figs. 6 and 7.

In both modifications, it should be noted that the light 40 is arranged in a recess away from the heat generated by the elements 10 and 12 and that the light is also protected against spillage. If desired, the wall defining the bottom of the trough 60 may be provided with a small opening therein through which any liquid which enters the trough might escape therefrom.

The particular form and construction of heating element and reflector shield 50 therefore are merely exemplary of elements of this type which may be employed in practicing the invention.

While I have illustrated and described a preferred embodiment of my invention, it is understood that this is capable of modification and I therefore do not wish to be limited to the precise details set forth but desire to avail myself of such changes and alterations as fall within the purview of the following claims.

I claim:

1. In an electric surface cooking unit of the embedded element type wherein sections of said unit are spaced to provide openings therebetween, a terminal block for such unit mounted on such unit and to which the current conductors for the embedded element are connected, said block having a receptacle for an electric light bulb thereon and a recess for such light bulb, a light bulb mounted in said receptacle and arranged in such recess, said terminal block being positioned relative to said unit so that said light bulb is arranged to throw a beam of light emitted therefrom through said openings in said unit, said bulb

being arranged to be energized when said element is energized.

2. An electric surface cooking unit as defined in claim 1 wherein a shield is provided for directing light from said bulb through said openings.

3. Apparatus according to claim 1 wherein a reflector forms a part of said recess.

4. In an electric surface cooking unit of the embedded element type wherein sections of said unit are spaced to provide openings therebetween, a terminal block for such unit mounted on such unit and to which the current conductors for the embedded element are connected, said block having a receptacle for an electric light bulb thereon and a recess for such light bulb, a light bulb mounted in said receptacle and arranged in such recess, said terminal block being positioned at one side of and relative to said unit so that said light bulb is arranged to throw a beam of light emitted therefrom through said openings in said unit, and means to confine the light emitted by said bulb to said unit, said bulb being arranged to be energized when said element is energized.

5. For use with an electric surface cooking unit wherein sections of said unit are spaced to provide openings therebetween; a terminal block mounted on such unit, said block having a receptacle for an electric light bulb thereon and a recess for such light bulb, a light bulb mounted in said receptacle and arranged in such recess, said terminal block being positioned relative to said unit so that said light bulb is arranged to throw a beam of light emitted therefrom through said openings in said unit, said bulb being arranged to be energized when said element is energized.

6. In an electric horizontal surface cooking unit of the embedded element type wherein sections of said unit are spaced to provide an upwardly facing opening therebetween, a light source arranged to be energized when the heating element of said unit is energized, said light source being supported from and arranged below said unit and relative to said opening so that light rays therefrom are directed upwardly through said opening in said unit in order to indicate when the element thereof is energized.

7. In an electric horizontal surface cooking unit of the embedded element type wherein said unit is formed to provide an upwardly facing light emitting port in the exposed horizontal surface thereof, a light source disposed remotely relative to said element and arranged to be energized when said element is energized, said light source being arranged below said unit and relative to said port so that light rays therefrom are directed upwardly through said port in said unit in order to indicate when the element thereof is energized, said light source being substantially concealed by a port of said unit and being supported thereby.

ARTHUR H. KITSON.
